WOODWORKING PLANE WITH CHIP
RELEASING MEANS

Joseph P. Zaidan, Philadelphia, Pa.

Application May 23, 1951, Serial No. 227,865

3 Claims. (Cl. 145—15)

1

This invention relates to an improved woodworking plane.

In a conventional woodworking plane used by carpenters the plane bottom is formed with a transverse slot through which the cutting blade extends, and it frequently happens in the planing of wood that the shavings clog up in the slot and impair the normal use of the plane. It is, therefore, an object of this invention to provide in combination with a woodworking plane, means whereby any clogging chips or shavings may be instantly released.

Another object of this invention is to provide in a woodworking plane a spring-pressed plate disposed forwardly of the cutting blade with an operating lever extending forwardly and about the front knob so that the plate may be raised to released position when any chips or shavings clog up the clearance slot.

With the above and other objects in view, my invention consists in the arrangement, combination and details of construction disclosed in the drawings and specifications, and then more particularly pointed out in the appended claims.

In the drawings:

Figure 1 is a detailed side elevation of a woodworking plane constructed according to an embodiment of this invention.

Figure 2 is a fragmentary sectional view taken on the line 2—2 of Figure 1.

Figure 3 is a sectional view taken on the line 3—3 of Figure 2.

Figure 4 is a fragmentary sectional view taken on the line 4—4 of Figure 3.

Figure 5 is a perspective view of the chip releasing device.

Referring to the drawing, the numeral 10 designates generally a woodworking plane of conventional construction which has a cutting blade 11 and a rear upstanding handle 12 secured to a bottom 13. A forward handle or knob 14 is secured to the forward end of the bottom 13, and the bottom 13 has disposed on the opposite longitudinal edges thereof upstanding side walls 15.

In conventional woodworking planes under certain conditions of the wood the chips or shavings cling to the keen edge 16 of the blade 11 and clog up the clearance space 17 which is formed transversely across the bottom 13.

In order to provide a means whereby any chips or shavings which may clog the clearance space 17, I have provided a vertically movable spring pressed plate 18 which is disposed in the transverse slot or opening 17.

Preferably the transverse slot or opening 17

2

is widened to a substantial degree forwardly of the keen edge 16 of blade 11 so that the plate 18 may be movably disposed forwardly of the blade 11. The plate 18 has extending upwardly or right angularly from the opposite ends thereof a pair of side members 19 which are formed with vertically disposed openings 20.

The inner sides of the side walls 15 have secured thereto vertically disposed guide members 21 which loosely engage through the openings 20 so that the plate 18 with the upstanding ends or sides 19 may be vertically moved as will be hereinafter described. When the plate 18 is in its lowermost and normal position with the lower surface thereof flush with the lower surface of the bottom 13 the connecting member 22 which extends across the upper end of the opening 20 will be disposed in abutting relation to the upper end of a guide member 21.

The U-shaped member which forms the plate 18 and the upstanding slide members 19 is adapted to be moved upwardly to a released position by means of a releasing lever 23 which is rockably mounted on an upstanding post 24 secured to the upper side of the bottom 13. The rear end of the lever 23 is reduced as indicated at 25, and the reduced end 25 loosely engages in an opening 26 formed in an upstanding lug 27 carried by the upper side of the plate 18.

The lever 23 extends forwardly from the supporting post 24 and is bent on a curvature as indicated at 28 so as to engage about the knob 14, and to terminate at its forward end adjacent the forward end of the bottom 13. The plate 18 is normally urged downwardly to a normal lower position by means of a pair of spring arms 29 which extend from a loop 30 which is disposed beneath the knob 14.

The spring arms 29 constantly urge the plate 18 downwardly to the limit permitted by the guides 21. As shown in Figure 5 the opposite ends of the plate 18 are formed with cutouts or inwardly projecting slots 31 which are of a depth such that the plate 18 with the slide members 19 may be vertically raised to remove the plate 18 from the plane for repair of the device or for other purposes. The plate 18 with the slide members 19 may be removed by withdrawing the pivot pin 35 on which the lever 23 is rockably mounted and then removing the lever 23 and also removing the spring members 29 by taking off the knob 14.

What is claimed is:

1. A woodworking plane comprising a bottom member, upstanding sides carried by the length-

wise edges of said member, said bottom member having a transverse opening, a cutting blade having the keen edge thereof projecting into said opening, a U-shaped member having the bight thereof disposed in said opening and the legs thereof confronting the inner faces of said sides, said legs having vertically elongated openings thereon terminating below the upper ends thereof, vertically disposed guides fixed to said sides and projecting into the openings of said legs, spring means constantly urging said U-shaped member downwardly, a lever, means carried by said bottom member engaging said lever between the ends thereof and rockably mounting said lever, and means connecting one end of said lever with said U-shaped member whereby rocking of said lever will raise said U-shaped member to shaving release position.

2. A woodworking plane comprising a bottom member, upstanding sides carried by the lengthwise edges of said member, said bottom member having a transverse opening, a cutting blade having the keen edge thereof projecting into said opening, a U-shaped member having the bight thereof disposed in said opening and the legs thereof confronting the inner faces of said sides, said legs having vertically elongated openings thereon terminating below the upper ends thereof, vertically disposed guides fixed to said sides and projecting into the openings of said legs, spring means constantly urging said U-shaped member downwardly, a lever, means carried by said bottom member engaging said lever between the ends thereof and rockably mounting said lever, and means connecting one end of said lever with said U-shaped member whereby rocking of said lever will raise said U-shaped member to shaving release position, said last mentioned means comprising a reduced end of said lever

5 and a lug carried by said bight having an aperture therein wherein said reduced end loosely engages.

3. A woodworking plane comprising a bottom member, a forward handle carried by said bottom member, upstanding sides carried by the lengthwise edges of said member, said bottom member having a transverse opening, a cutting blade having the keen edge thereof projecting into said opening, a U-shaped member having the bight thereof disposed in said opening and the legs thereof confronting the inner faces of said sides, said legs having vertically elongated openings thereon terminating below the upper ends thereof, vertically disposed guides fixed to said sides and projecting into the openings of said legs, spring means constantly urging said U-shaped member downwardly, a lever, means carried by said bottom member engaging said lever between the ends thereof and rockably mounting said lever, and means connecting one end of said lever with said U-shaped member whereby rocking of said lever will raise said U-shaped member to shaving release position, said lever having an arcuate body portion extending peripherally about said forward handle to facilitate actuation thereof.
